UNITED STATES PATENT OFFICE.

ROBERT G. WEISSEL, OF OAKLAND, CALIFORNIA.

LEVER-LOCK.

1,235,863.

Specification of Letters Patent. Patented Aug. 7, 1917.

Application filed May 29, 1917. Serial No. 171,643.

To all whom it may concern:

Be it known that I, ROBERT G. WEISSEL, a citizen of the United States, residing at Oakland, in the county of Alameda and 5 State of California, have invented certain new and useful Improvements in Lever-Locks, of which the following is a specification:

The present invention relates to a lock device for levers and more particularly to a 10 device for locking a motor vehicle gear shift lever from movement by unauthorized persons when it is desired to leave a motor vehicle unattended.

15 The invention consists broadly in providing a lock structure capable of attachment to any well known type of gear shift lever, and designed when in operative position to have engagement with a stationary portion 20 of the vehicle, preferably the lever guide, to lock the lever from operative movement, and preferably in what is commonly termed "reversed position."

The invention comprises a casing within 25 which is mounted a locking bolt and which is connected through a pivotal link with a latch member capable of operation to actuate the locking bolt, and when in one position capable of movement for reception into 30 a key controlled locking mechanism.

With the above mentioned and other objects in view, the invention consists in the novel construction and combination of parts hereinafter described, illustrated in the accompanying drawings and pointed out in the claims hereto appended; it being understood that various changes in the form, proportion, size and minor details of construction within the scope of the claims may be 35 resorted to without departing from the spirit or sacrificing any of the advantages of the invention.

To more fully comprehend the invention, reference is directed to the accompanying 40 drawings, wherein—

Figure 1 is a view in side elevation of the preferred embodiment of my invention, applied to a gear shift lever.

Fig. 2 is a view in end elevation.

50 Fig. 3 is a view in top plan.

Fig. 4 is a vertical sectional view taken centrally through the lock mechanism there- 60 of with the mechanism in unlocked position.

Referring more particularly to the several views of the drawings, wherein like characters of reference designate corresponding parts, 1 indicates a suitable gear shift lever of the well known type, and the same projects through a housing 2, preferably formed with the usual H-slot guide 3 in 65 which the lever moves; the slot controlling the operative movement of the lever. In the drawing the lever is illustrated in operative position, and in which position the shiftable gears, controlled thereby, are preferably in engaged relation to cause the rearward or reverse movement of the vehicle.

Secured to and movable with the lever at one side thereof, immediately above the upper surface of the housing 2, is my improved lock mechanism, consisting of the side plates 4 which are held in parallel spaced relation in any suitable manner; said side plates being permanently secured to the lever by a suitable attaching means 5, preferably in the form of a rivet. Positioned between the plates 4 and adapted to have vertical lineal movement is a locking bolt 6 having an offset lower end 7, and provided with an elongated guide opening 8 through 70 which passes a pin 9 supported by the plates 4, and providing a guide for the bolt. The offset portion of the locking bolt is adapted, when the same is moved into operative position, as in Fig. 1, to be received in an opening 10, formed in the upper surface of the housing 2 at one side and adjacent the rear edge of the reverse slot opening in said cover or housing. The upper end of said lock bolt is pivotally connected, as at 11, to one end of a link 12, fulcrumed as at 13, and pivotally carrying, as at 14, at its opposite end an operating member 15 formed with an L-head 16 providing a latch which is formed in its outer face with a notch 17.

95 The member 15 is adapted to be manually swung outwardly and upwardly on its pivotal point 14 from the unlocked position, as illustrated in Fig. 4, and thence moved linearly and inwardly to a position as in Fig. 100

1, which movement oscillates the link 12 on its fulcrum 13 which causes a separation of the pivoted ends of the keeper member and bolt and a lineal movement of the locking bolt 6 downwardly to the position as in Fig. 1 of the drawings, at which time the offset end 7 thereof is received in the opening 10 to lock the lever from movement. When in this locking position the head 16 of 10 the latch member is adapted to be forced inwardly to enable the notch 17 thereof to be engaged by a suitable pawl 18 within the key controlled lock mechanism 19, at which time the lever is locked from operative movement.

Between the plates 4 are mounted the springs 20 and 21, the spring 20 being coiled about the rivet 5 and provided at its outer free end with a raised portion 22, which is 20 adapted to be received in the notch 17 and retain the operating member 15 in its retracted position and to prevent the same from rattling, and the free rear end of said spring bears upwardly on the locking bolt 25 6 to normally maintain the same in its raised or unlocked position. The spring 21 is also coiled about the lower rivet 5 and the free end thereof normally abuts against the rear face of the operating member 15 to 30 assist in removing the same from between the plates when the outer free end of the spring 20 is manually depressed to withdraw the portion 22 thereof from the notch 17. In order to throw the member 15 from 35 the locking mechanism 19 on the operation of the barrel 23 thereof, a spring 24 is employed.

It will be apparent that I have provided a construction composed of very few elements and it is capable of attachment to a lever at very little expense; one which is capable of operation to throw the locking bolt thereof into either operative or inoperative position, and one wherein the 45 operating means also serves as a latch for engaging the locking member. While I have illustrated my lock as applied to a lever operating through a guide of the H-type, it is apparent that the same may be applied 50 equally as well to a construction of the ball and socket type.

By pivotally connecting one end of the locking bolt and keeper member to the opposite ends of a fulcrum link, the oscillation of the link, due to manual movement of the latch, causes a separation of the pivoted ends of said members, and by positioning the key controlled locking mechanism a distance from the fulcrum point of 55 60 the connecting link, a slight oscillation of the link is required, when the bolt is in unlocked position, to enable the latch member to be received within the locking mecha-

nism, which movement causes a lineal movement of the locking bolt to project the free 65 end thereof into the opening in the guide plate.

Having thus described my invention, what I claim as new and desire to protect by Letters Patent is:—

1. In combination with a movable member, a stationary member associated therewith and provided with a locking bolt receiving opening, a locking mechanism carried by the movable member to lock the 75 same to the stationary member and comprising a fulcrumed link, a lineally movable locking bolt pivotally connected to one end thereof for the reception of its free end within said opening, an operating latch 80 member pivotally connected at one end to the other end of said link, and a locking means with which said latch co-operates, the movement of said keeper into engagement with said locking means causing a lineal 85 movement of said locking bolt for reception within said opening.

2. In combination with a movable lever, a stationary member through which the lever extends and relatively to which the same 90 operates, mechanism carried by the lever above said stationary member for locking said lever thereto and comprising a fulcrumed link, a lineally movable locking bolt 95 fulcrumed at one end to said link and movable lineally to the lever for engaging said stationary member, a manually movable latch pivotally connected at one end to said link and adapted for swinging movement on its fulcrum, and locking devices for 100 receiving said latch on the movement of said bolt into locked engagement with said stationary member.

3. In combination with a lever, a stationary member through which the same extends and relatively to which the same operates, a lever lock carried by the lever above said stationary member and comprising a fulcrum link, a lineally movable locking bolt 105 pivotally connected at one end to one end 110 of said link, a locking mechanism above said link, a latch member pivotally connected at one end to the opposite end of said link and for engagement at its free end with said locking mechanism, the movement of said latch into engagement with said locking mechanism causing a movement of said locking bolt into locked engagement with said stationary member.

4. In combination with a lever, a stationary member through which the same extends and relatively to which the same operates, a lever lock carried by the lever above said stationary member and comprising a fulcrum link, a lineally movable locking 115 120 bolt pivotally connected at one end to one

end of said link, a locking mechanism above said link, a latch member fulcrumed at one end to the opposite end of said link and capable of swinging movement on its fulcrum to lie below or above said link, the movement of said latch into engagement with said locking mechanism oscillating said link to separate the adjacent ends of said bolt and latch to move said locking bolt into locked engagement with said stationary member, and releasable means for retaining said latch in a position below said link.

In testimony whereof I have signed my name to this specification in the presence of two subscribing witnesses.

ROBERT G. WEISSEL.
